MINERAL SEPARATOR

Hugo A. Mau, Milwaukee, Wis.

Application September 14, 1942, Serial No. 458,308

4 Claims. (Cl. 209—209)

This invention relates to a mineral separator. In certain locations ore bearing or mineral bearing material is found which is of such a low grade, that is, contains such a low percent of the mineral sought, that it does not pay to operate on this material with the ordinary apparatus and processes usually employed. The difficulty is further enhanced by the fact that frequently there is neither water available nor electric or other power and yet there is a quantity of valuable material that could be obtained from such locations. In fact, in certain of these locations all water used has to be hauled or otherwise transported and there is great difficulty in avoiding loss of water in the normal heretofore known operations.

This invention is designed to provide a mineral separator which can be employed under the above outlined severe conditions.

Further objects of this invention are to provide a separator which uses the water over and over again and thereby conserves the water, in which in the normal operation of the apparatus there is substantially no loss of water, in which collection chambers are provided—one for the mineral or material to be obtained and the other for the undesirable or waste material, such chambers being freely removable from the apparatus without loss of water.

Further objects are to provide a mineral separator which is not power operated but which is manually operated, which efficiently handles low grade material, which is freely portable, and which may be easily cleaned without waste of water.

In greater detail objects of this invention are to provide a mineral separator which depends for its operation upon the relative time required for different materials substantially freely falling through a vertical distance in water to pass over a given distance and to provide automatic means for insuring the discharge of material which requires a lesser time for its travel from material which requires a greater time for its travel through the same vertical distance in water or other liquid.

Further objects are to provide a mineral separator which may be operated by unskilled operators, which is wholly automatic in its operation, which may be adjusted to separate different types of materials, and which automatically adjusts itself for any change in the specific gravity of water which may occur as the water picks up soluble material during the normal course of the operation of the apparatus.

Further objects are to provide a mineral separator which is rugged, which is freely portable, which cannot be easily damaged, and which does not require delicate adjustments though it will

effect relatively sharp separation of the different materials.

An embodiment of the invention is shown in the accompanying drawings, in which:

5 Figure 1 is a vertical elevation, partly in section with parts broken away, showing the mineral separator.

Figure 2 is a sectional view on the line 2—2 of Figure 1.

10 Figure 3 is a view looking down on the top portion of the structure shown in Figure 1.

Figure 4 is a sectional view on the line 4—4 of Figure 1.

15 Figure 5 is a sectional view on the line 5—5 of Figure 1.

Figure 6 is a sectional view on the line 6—6 of Figure 4.

20 Figure 7 is a view, partly broken away, of the lifting rod by means of which the timing weight may be raised.

Referring to the drawings, it will be seen that the device comprises a vertical chamber 1 which may be slightly conical if desired and which may be rectangular, round, or of other shape in horizontal cross-section. This chamber opens at its top into a relatively small hopper 2 which is of approximately the same size as the upper end of the chamber. The hopper 2 is surrounded by an upper open chamber 3 of considerably larger size to which it is attached by means of spacing blocks 2'. The hopper 2 is normally closed by means of a pair of horizontally slidable discharge members or partitions 4 whose inner ends normally rest on a substantially V-shaped transverse bar 5 and which are adapted to be automatically slid outwardly in opposite directions to discharge all of the material deposited in the hopper 2 at a given instant, as will be explained hereinafter.

25 30 35 40 45 50 The chamber 1 constitutes a separation chamber for the material as will appear hereinafter. As stated, it may be of any desired cross-sectional contour and is preferably slightly tapered as shown. The form shown is substantially rectangular in contour as will appear as the description proceeds.

The lower end of the separation chamber 1 opens into an intermediate chamber 6 and it is preferable to have the lower end of the separation chamber 1 project downwardly into and below the upper plate 7 of the intermediate chamber 6. Two discharge conduits open outwardly in divergent directions from the lower portion of the intermediate chamber 6, the larger of which is indicated by the reference character 8 and the smaller of which by the reference character 9. A swinging funnel-shaped, downwardly converging diverting member 10 is rigidly carried by a revolvably mounted rock shaft 11 which projects outwardly from the intermediate cham-

ber 6, as shown most clearly in Figure 4. The rock shaft 11 is provided with an arm 12, see Figures 4 and 6, to which a spring 13 is attached, thereby biasing the diverting member 10 towards the larger discharge conduit 8. The diverting member 10 is normally held in the position shown in Figure 1 so as to initially discharge into the smaller diverting conduit 9, though it is spring biased towards the other diverting conduit 8 as previously described. The diverting member 10 is normally held latched in the position shown in Figure 1 by means hereinafter described.

The diverting conduits or chutes 8 and 9 open at their respective ends into relatively larger and smaller collecting chambers indicated generally by the reference characters A and B. These collecting chambers A and B are provided with top plates 14 and 15 respectively. The bottom portion of the collecting chamber A is a relatively large vessel 16 which may be bolted as indicated at 17 or otherwise removably secured to the top plate 14, a suitable gasket being provided if desired. The collecting chamber B may comprise a glass vessel 18 which is detachably attached to the cover plate 15. For example, it may be a glass vessel 18 which is removably attached by screw thread means to the cover plate 15 as shown in Figure 1.

Means are provided for closing the lower openings of the diverting conduits 8 and 9 when desired. For example, the conduit 8 may have its lower end closed by means of a valve member 19 which may be of suitable composition, of rubber or other material. This valve member is carried by a threaded stem 20 provided with an upper manipulating hand wheel 21, whereby the valve may be moved into open or closed position, a suitable packing gland being provided as indicated.

The lower end of the diverting conduit 9 may be closed by means of a similar valve 22 which also is carried by a screw threaded stem 23 provided with a manipulating hand wheel 24 at its upper end, a suitable packing gland being provided as indicated. Preferably the valves 19 and 22 remain open throughout the successive operations of the apparatus. They are only closed when it is desired to remove the collecting chambers A and B.

Any suitable means may be provided for simultaneously opening the discharge members 4 at the upper end of the separating chamber 1 and at the base of the hopper 2. In the form of the invention shown means are provided for simultaneously and automatically sliding these members 4 outwardly in opposite directions so as to discharge all of the material in the hopper substantially instantaneously. This means may comprise two pairs of levers 25 and 26, each pair being rigidly carried respectively by the rock shafts 27 and 28. The lower ends of the levers 25 and 26 are joined by small links, as indicated at 29 and 30, to the members 4.

At the side of the apparatus the two rock shafts 27 and 28 rigidly carry levers 31 and 32 whose ends are adjacent and slotted and receive a pin 33 carried by a downwardly urged slide 34, suitably guided in the track like member 35 and spring urged downwardly by means of the spring 36. Normally the slide 34 is held latched in its upper position by means of the latch 37, see Figure 2, which is urged towards latching position by the spring 38 and which is adapted to be tripped by the handle 39.

It is to be noted from reference to Figures 1 and 3 that the rock shaft 27 is provided with a

small lever 25' which is attached by means of a cable or other suitable member 40 to a latch 41. The latch 41 may be spring urged to the right as viewed in Figure 1, or may be manually pushed to the right as desired. This latch normally is positioned beneath the enlarged head 42 of a screw threaded rod 43 which is screw threaded into a timing weight indicated generally at C.

This timing weight C may be elongated and may be provided with a lower rounded end. After the proper adjustment between the spacing of the timing weight C and the enlarged head 42 of the threaded screw rod 43 has been obtained by screwing the rod into or out of the timing weight, a lock nut indicated at 44 is tightened to thus lock the rod and the timing weight in their adjusted position. The timing weight C may be composed of a single unit if so desired or may be made of a group of units consisting of a lower main unit 45 and additional disk like units 46. It also may be made hollow or solid, depending upon the total weight desired. Obviously by adding disks 46 of heavy material, such as lead or iron, the total weight may be increased materially, or if desired, light metal disks or even composition non-absorbent disks could be added to increase the size of the timing weight C without materially increasing its total weight. Thus the specific gravity of the assembly constituting the timing weight C may be adjusted as desired, depending on the type of material to be separated as will appear as the description proceeds.

A vertical timing chamber or guide chamber 47 is provided and is connected at its upper and lower ends by means of relatively large pipes 48 and 49 respectively with the chambers 3 and 6. It is intended that the device be filled with water or other suitable liquid, water being preferred, to approximately the level indicated by the dotted line 50. Thus the timing weight C and the material both fall downwardly when released through the water to adjacent the lower end of the separating chamber 1 and the timing chamber 47.

The diverting member 10 is connected by means of a link 52, see Figure 1, with a guide 53 which rides on the bottom of the pipe 49. It is normally held latched by means of the detent 54. This detent is provided with an arm 55 extending transversely adjacent the lower portion of the timing chamber or guide chamber 47 and the arm 55 is spring pressed upwardly by means of the spring 56.

The lower portion of the timing chamber is closed by a removable plate 57 which is removably bolted to the lower end of such chamber, a suitable gasket being preferably interposed.

The timing and guide chamber 47 is provided with guide means of any suitable type for guiding the timing weight C. Preferably the guide chamber is provided with a pair of inwardly directed opposed ribs or guide strips 58 and the timing weight C is provided with opposed grooves to loosely and freely receive the guide strips 58.

The spring 56 serves an additional function of cushioning the timing weight when it strikes the trip arm 55 and releases the trip pawl 54 so that the trip member composed of the arm 55 and the pawl 54 will release the diverting member 10, which under the influence of the spring 13, see Figure 6, will rock from the full line position over the small diverting conduit 9 to the dotted line position over the large diverting conduit 8, it being noted that the conduits join each other

and form a relatively sharp V-shaped dividing portion 59, see Figure 1.

Manual means are provided for resetting the diverting member 10. This manual means may consist of a manually operable lever 60, see Figure 6, rigid with the rock shaft 11 so that the diverting member 10 may be manually rocked from its dotted line position in Figure 1 to its full line position, at which time the pawl 54 will engage the guide member 53 and thus temporarily latch the diverting member 10 in its full line position.

In order to raise the timing weight C from its lowermost position to its uppermost position, any suitable instrument may be employed. For example as shown in Figure 7, a rod 61 may be provided with a plurality of spring clips 62 at its lower end which are equipped with cam like portions 63 and shouldered portions 64 so that the cam like portions will cause the spring clips 62 to diverge when the retracting or lifting rod 61 is forced downwardly through the timing chamber 47 into engagement with the enlarged head 42 of the timing weight C.

Thereafter the shouldered portion 64 will engage beneath such head and thus the timing weight C may be raised to its elevated position so that it may be again latched by the latch member 41, the latch member 41 being, as stated, either manually pushed to the right or else spring pressed to the right. It is sometimes desirable to have the latch member 41 manually pushed to the right so that it can remain in its withdrawn position to give additional freedom in inserting the retracting rod 61 down into the timing chamber 47.

In order to explain the theory of operation of this apparatus, assume for an instant that material of the same specific gravity as that of the timing weight C is released at the upper end of the separating chamber 1 at the same instant that the timing weight C is released. Under these conditions the timing weight and the material will both travel substantially the same vertical distance downwardly in the same interval of time. If the released material is of less specific gravity than that of the timing weight C, it is apparent that the timing weight will arrive at its tripping position, tripping the diverting member 10 prior to the arrival of the material at the diverting member 10 so that the material will be discharged into the conduit or chute 8 and from thence into the collecting chamber A. On the other hand, if the material released at the same time as the timing weight is of greater specific gravity than that of the timing weight C, it is apparent that such material will arrive at the diverting member 10 and be diverted into the conduit or chute 9 prior to the time that the timing weight C trips such diverting member.

This principle is employed in separating materials of different specific gravities, such for example as gold or sand. Under these conditions, the adjustment of the apparatus is such that the timing weight arrives at its diverting member tripping position after the gold arrives at the diverting member, so that the gold is diverted into the conduit or chute 9 and the sand or other material of this type is diverted into the conduit or chute 8, so that the gold will collect in the collecting chamber B and the sand or similar material will collect in the chamber A.

With this apparatus it has been found that separations can be made between a vast number

of different minerals due to the fact that the different minerals have different specific gravities and the apparatus may be adjusted to effect separation between any particular group of materials which have different specific gravities and consequently which have different intervals of time required for their transit downwardly through the column of water in the separating chamber 1 to the diverting member 10.

One of the ways in which this adjustment can be made for different materials is to vary the total weight of the timing member C with reference to its total size, thus varying its specific gravity. For small adjustments it is possible to raise or lower the timing weight C with reference to the head 42, see Figure 1, so that the timing member starts at a slightly greater or a slightly lower point as required.

Assuming the parts are in position for operation, a load of material is deposited in the hopper 2 and rests on the bottom slides 4. The operator then trips the latch 31, thus releasing the slide 34, see Figure 2. The slide 34 descends and causes the pairs of levers 25 and 26 to substantially instantly separate the plates or material releasing members 4 so that the material in the hopper 2 is discharged substantially instantaneously into the upper end of the separating chamber 1. At the same instant the latch 41 is withdrawn from beneath the head 42 and releases the timing weight C which descends. The material desired to be recovered arrives at the diverting member 10 before the timing weight C trips such diverting member and such material is passed downwardly into the collecting chamber B.

Thereafter the timing weight trips the diverting member 10 prior to the arrival thereof by the other material and such other material or remaining material is discharged into the receiving chamber A. In order to reset the apparatus, the operator, through the medium of the lever 65 see Figures 1 and 3, resets the slides 4, this operation elevating the member 34, see Figure 2, until such member is again latched by means of the pawl 37. Thereafter the operator inserts the retracting rod 61 into the timing chamber 47 and lifts the timing weight C to its uppermost position and thereafter causes the latch 41 to engage beneath the enlarged head 42. The operator then, through the medium of the lever 60 see Figures 4 and 6, rocks the shaft 11 to thereby rock the diverting member 10 to the right as viewed in Figure 1, the pawl 54 then latching such diverting member in the full line position of Figure 1. The apparatus is now ready for a subsequent operation.

By having the timing chamber 47 and the separating chamber 1 in free communication at their upper and lower ends, it is apparent that any change in the density of the water due to absorption of solubles by the water will be uniform throughout the entire water system of the apparatus as there is a free circulation of water provided by the construction.

When it is desired to empty either of the chambers A or B, the appropriate valve 19 or 22 is first closed. Thereafter the chamber 16 or 18 is detached and the excess water poured back into the chamber 3. Thereafter the collected material is removed from the chamber 16 or 18 and the chamber is replaced and the appropriate valve 19 or 22 is again opened.

Substantially no water is lost even when it is necessary to empty the chambers A and B. On the other hand, through a long series of suc-

sive operations it is not necessary to empty either chamber as they may be made as large as need be and therefore during these successive operations there is no water lost whatsoever.

It is to be noted that when the apparatus is to be thoroughly cleaned out, the water is poured out of the apparatus and the chambers 16 and 18 are removed and their valves left open and the plate 51 is removed from the lower end of the timing chamber 1. This enables any collected material deposited anywhere in the apparatus to be readily removed.

Thus it is possible to keep the apparatus in a very clean condition without danger of ultimate clogging.

It sometimes happens that in separating materials some portions of which are relatively flat, that the flat portions do not always travel downwardly in a straight line but tend to travel back and forth in a zigzag line. In order to avoid this result, vertical baffles 1', see Figure 1, may be employed and extend from one side of the apparatus to the other so that when a piece of sheet material tends to travel in a zigzag path, it immediately strikes one of the baffles or the outer wall and is turned vertically so that it will travel downwardly.

The particular material chosen as an illustration, namely, gold and sand, is not to be considered as limiting for the apparatus, as stated, can be successfully used to effect separation between many widely different materials.

The apparatus is particularly useful where water is very scarce and where the material is of a relatively poor grade, that is to say, a small percent of the total material being that which it is desired to recover or separate.

The device is manually operable throughout and does not require any fragile or delicate parts. It is easily transported. The device may be provided with any suitable types of supports in order to hold it in its upright position. Such supports have been omitted from the drawings as they form no part of the essential structure of the apparatus and may, as stated, take any form desired. The apparatus is also freely portable and may be transported from one claim to another claim as required. It conserves water to a very high degree and consequently is especially useful as hereinbefore described.

It will be seen that a novel mineral separator has been provided by this invention which is easy to operate, which may be efficiently used to effect any desired separation of materials even from low grade claims or from claims in which there is only a small percent of the desired material.

It will be seen further that the device can be easily operated by a single operator and that it conserves water, and that it is rugged and substantially fool-proof.

Although this invention has been described in considerable detail, it is to be understood that such description is intended as illustrative rather than limiting, as the invention may be variously embodied and is to be interpreted as claimed.

I claim:

1. A mineral separator comprising a separating chamber adapted to contain a liquid, means for discharging material to be separated into the upper portion of said separating chamber, a first and a second receiving means for respectively receiving material that descends through said separating chamber during a predetermined interval of time and after a predetermined in-

terval of time, diverting means for selecting the receiving means into which the descending material may pass, and automatic timing means including a timing weight arranged to descend through the same liquid contained in said separating chamber, the operation of said diverting means being controlled by said automatic timing means.

2. A mineral separator comprising a separating chamber and a timing chamber adapted to contain a liquid, a hopper for the reception of material to be separated adjacent the upper end of said separating chamber, a timing weight normally held adjacent the upper end of said timing chamber, means for simultaneously discharging the material into the upper portion of said separating chamber and releasing said timing weight, receiving means for receiving the separated material and the remaining material, and a diverting member adjacent the lower portion of said separating chamber normally arranged to discharge the material into one of said receiving means and automatically moved to discharge material into the other receiving means when said weight has descended to a predetermined point in said timing chamber.

3. A mineral separator comprising a separating chamber and a timing chamber adapted to contain a liquid, said separating chamber and said timing chamber communicating at their upper and lower portions, a hopper for the reception of material to be separated adjacent the upper end of said separating chamber, a timing weight normally held adjacent the upper end of said timing chamber, means for simultaneously discharging the material into the upper portion of said separating chamber and releasing said timing weight, receiving means for receiving the separated material and the remaining material, and a diverting member adjacent the lower portion of said separating chamber normally arranged to discharge the material into one of said receiving means and automatically moved to discharge material into the other receiving means when said weight has descended to a predetermined point in said timing chamber.

4. A mineral separator comprising a separating chamber and a timing chamber communicating at their upper and lower portions and adapted to contain a liquid, a hopper for the reception of material to be separated located adjacent the upper end of said separating chamber, a timing weight normally held adjacent the upper end of said timing chamber, means for simultaneously discharging the material from said hopper into the upper portion of said separating chamber and releasing said timing weight, a first and a second receiving means located adjacent the lower end of said separating chamber and communicating therewith, a diverting member located adjacent the lower end of said separating chamber and normally positioned to divert the material passing downwardly through said separating chamber into said first receiving means and biased to position to divert the material into said second receiving means, and latch means for holding said diverting member in said first mentioned position, said latch means being located adjacent the lower portion of said timing chamber and being tripped by said weight to release said diverting means when said weight arrives at a predetermined point adjacent the lower end of said timing chamber.

HUGO A. MAU.
